Application July 13, 1953, Serial No. 367,627

12 Claims. (Cl. 189—1)

The present invention relates to air processing systems and, more specifically, to enclosures or hood structures utilized in such systems.

In certain industries, particularly in the pulp and paper industry, it is common practice to provide some means of processing and recirculating the moist air which arises from a drying machine or the like. In order to at least partially confine and evacuate such air the usual procedure is to provide some kind of air enclosure or hood over the top of the drying machine and also provide some means of exhausting the air so confined.

While these prior art structures are effective in preventing excessive condensation and also at least partial control of the air, these have been designed so that they only partially hood the machine leaving the bottom portion open. The main purpose of providing a hood or enclosure over a machine of this nature is to provide a means whereby the temperature and vapour content of the air surrounding the machine may be controlled more closely to improve the operating conditions for the machine.

One of the main reasons why prior art hood structures of this nature were not designed to totally enclose, for example, high speed paper drying machines, is that it is necessary to provide for instant access to a machine of this type so a break, that may occur in the paper web, can be attended to before it piles up. Such breaks must be cleared as soon as possible so that the paper web can continue to run through without having to stop the machine. It is for this reason that in most paper mills the drying rolls are almost universally open-type machines so as to enable the machine tender to watch the sheet and handle breaks that might occur on the drying rolls.

Accordingly, it was thought that if such machines were totally enclosed it would be impossible to have ready access to the drying rolls and other operating portions as is required.

As is well known, the presently accepted method for drying of a paper web on a high speed paper machine is carried out by passing the web over a series of hot rolls which are heated internally by steam. This results in the formation of a large volume of water vapour which is absorbed by warm air near the machine and is usually allowed to escape through openings in the roof, either by natural draft or by suction draft caused by any air-moving device drawing the hot air and vapour through a hood placed immediately over the machine and discharging the moisture-laden air outdoors.

As will be appreciated, a considerable volume of heated air is required to carry away such vapours. For example, a machine producing approximately a hundred tons of newsprint every twenty-four hours requires the evaporation of two hundred tons of water per day. An average of approximately one hundred thousand cubic feet of air per minute is necessary to carry away these vapours. In accordance with the present invention, by the use of an overall hood, the energy in so much heated air and

2

warm vapour may be conserved and the necessary volume of air handled can be reduced by at least fifty percent.

Further, the conditions of paper manufacture can be improved by closer control of air conditions through conditioning of the air as confined by such a hood structure. The speed of paper drying machines may be increased when hooded in accordance with the present invention by the speedier drying and the elimination of outside drafts etc., from the drying rolls.

10 The present hood structure is designed so that while affording complete protection to the machine on all sides also provides means whereby access can be had to either or both sides of the machine quickly and easily.

Accordingly, the invention comprises an overall hood structure adapted for use in enclosing a high-speed drying machine of the type having at least a major portion extending upwardly from a mill floor. More specifically, in a preferred construction the present hood structure consists of a self-supporting enclosure, mounted directly on the frame of the machine, which includes a roof portion of a length substantially equal to the machine to be enclosed and a width slightly greater than the machine so as to extend beyond the machine at each side. Side walls are provided which are co-extensive

20 in length with the roof portion and extend from the mill floor to the roof portion. End walls are provided which connect the roof and side walls at each end and include side portions extending from the mill floor to the roof and a central portion extending from the roof and terminating

25 short of the mill floor to provide entry and exit passages for the feeding of material through the machine to be hooded.

In accordance with the present invention, each of the 30 enclosure's side walls includes a plurality of movable segments and there are means provided for automatically moving the segments to provide access to the machine. Preferably, the side wall segments consist of a plurality of juxtaposed upper and lower panels which extend the length of the side wall. In the preferred construction, on

35 one side wall the lower panels are mounted for vertical sliding movement relative to the upper panels and the upper panels may be fixed or mounted for horizontal sliding movement relative to each other. In the other sidewall either or both of the upper and lower panels are mounted for horizontal sliding movement relative to each other.

The center portion of one of the end walls includes 40 a lower portion also mounted for sliding movement in a vertical direction so that the height of the entry passage to the machine at the enclosure and may be varied to suit the particular machine over which the enclosure is mounted.

The enclosure structure itself including the roof, side 45 walls and end walls are preferably made of panels of corrugated aluminum sheet mounted over a suitable steel framework. The roof is of two-ply insulated construction while the movable segments or sliding doors are of opposed double-ply corrugated aluminum sheet construction so as to provide the maximum in strength, insulation, and rigidity while being as light as possible.

The preferred means for raising and lowering the vertically slidably mounted side wall panels or doors comprises essentially a system of inter-connected shafts and pulleys which are driven by suitable electric motors, the individual doors being provided with rollers fitting into and guided by vertical channels or tracks secured to the side wall frame work.

In the preferred construction, the lower side wall doors are arranged to be raised in several sections; for example, the lifting mechanisms for three adjacent doors can be coupled and driven by a single motor. Prefer-

ably, the controls for the driving motors are such that each section can be raised individually or all the sections simultaneously.

DETAILED DESCRIPTION

Having thus generally described the nature of the invention, particular reference will be made to the accompanying drawings showing by of illustration a preferred construction in accordance with the invention of an enclosure hood structure in combination with a high-speed paper drying machine, and in which:

Figure 1 is a diagrammatic view in perspective elevation of a complete hood structure in accordance with the invention as it would appear in operative relationship over the drying section of a high-speed paper machine looking from the "wet" end of the machine.

Figure 2 is a view in plan of the construction shown in Figure 1.

Figure 3 is a view in side elevation of the construction shown in Figure 1 with all the doors shown in closed position.

Figure 4 is a view in side elevation corresponding to Figure 3 of the opposite side of the machine showing the alternative arrangement of doors mounted for sliding horizontal movement.

Figure 5 is a diagrammatic view of one end of the hood structure shown in Figure 1, which is positioned adjacent the "wet" end of the drying machine.

Figure 6 is a diagrammatic view corresponding to Figure 5 showing the opposite end wall of the hood structure adjacent the "dry" end of the machine.

Figure 7 is a sectional view of Figure 4 along the line 7-7 to illustrate in more detail the internal construction and disposition of the upper set of horizontally slideable doors.

Figure 8 is a sectional view of a portion of Figure 4 along the line 8-8 to illustrate in more detail the construction and arrangement of the lower set of horizontally slideable doors.

Figure 9 is an enlarged sectional view of Figure 2 along the line 9-9 to show a typical transverse section through the complete hood structure showing the relative position of the drying rollers and frame of the machine in broken lines.

Figure 10 is a sectional view of Figure 9 along the line 10-10 to show a typical mounting arrangement between a supporting beam and the roof panels.

Figure 11 is an enlarged diagrammatic view, partially in section, along the line 11-11 of Figure 3 to show in more detail the construction of the supporting framework and the counterweight and guiding arrangement for a vertically slideable door.

Figure 12 is a sectional view of Figure 11 along the line 12-12 to show in more detail the guiding track and rollers for the vertically slideable doors.

Figure 13 is a diagrammatic view mainly in section of the opposite side wall of the hood structure as indicated along the line 13-13 of Figure 4.

Figure 14 is an enlarged diagrammatic view of a portion of a vertically slideable door showing the connection to the counterweight and to the door-lifting cable.

Figure 15 is a plan view of the construction shown in Figure 14, partially in section, along the line 15-15.

Figure 16 is a sectional view of Figure 3 along the line 16-16 to show in enlarged detail the construction of the vertically slideable doors.

Figure 17 is a diagrammatic view of adjacent portions of two of the shaft arrangements on which the cable-winding pulleys are attached with a flexible coupling disposed between the adjacent shafts.

Figure 18 is a diagrammatic view corresponding in location to Figure 17, with the exception that no coupling arrangement is shown between the adjacent shaft portions.

Figure 19 is an enlarged diagrammatic view partially in section to show a typical arrangement utilized to drive

the cable-winding pulleys for the vertical-lifting doors.

Figure 20 is a diagrammatic view partially in section of a cable winding pulley and the upper portion of a vertically sliding door corresponding to the portion shown in Figure 14.

Figure 21 is a sectional view of the end wall of the enclosure as shown in Figure 5 and along the line 21-21 to show in more detail the central lifting panel adjacent the "wet" end of the machine.

Figure 22 is a cross sectional view of the end wall of the hood structure adjacent the "dry" end of the machine as shown in Figure 6 along the line 22-22.

Figure 23 is an enlarged cross sectional view of a typical juncture between the fixed end panels of the structure shown in Figure 22.

Figure 24 is a view, in plan, of the chain and pulley arrangement utilized to raise the vertically sliding centre portion of the end wall construction shown in Figure 1 along the line 24-24.

Figure 25 is a sectional view of Figure 6 along the line 25-25 to illustrate the construction of the enclosure end wall at the "dry" end in more detail.

Figure 26 is a diagrammatic view in front elevation of a typical section of the vertically lifting doors on one longitudinal side wall.

Figure 27 is a section along the line 27-27 of Figure 6 to show in more detail the internal construction of the access door in the end wall.

With particular reference to Figures 1 through 6 and Figure 9, a preferred hood construction in accordance with the present invention is shown as comprising essentially a roof portion 10, longitudinal side wall portions 12 and 14, and end walls 16, 18, which are mounted over and supported by a steel framework connected to and extending from the upper frame of the machine enclosed.

In the structure illustrated, the machine enclosed is a high-speed paper drying machine having drying rollers "B" mounted on a supporting frame "C" with the lower portions of the bottom dryer rolls "D" of the machine descending below the mill floor into the machine pit (not shown).

The hood structure shown is mounted directly on upper frame members of the machine frame "C" so that the portion of the machine extending above the mill floor "A" is enclosed along each side and a major portion of both ends. The roof portion 10 is of substantially equal length to the machine and is greater in width so as to extend beyond the machine at each side. The side walls 12 and 14 are substantially coextensive in length with the roof 10 and extend from the mill floor "A" to the roof at the eaves portions 9. The end walls 16 and 18 connect the roof 10 and side walls 12 and 14 at each end with the end wall 16 being disposed at the "wet" or entry end of the machine and the end wall 18 disposed at the "dry" or discharge end of the machine. Each of the end walls 16, 18 include side panels at each side which extend from the mill floor "A" to the roof 10 and each has a central portion which terminates short of the mill floor "A" to provide entry and discharge passages for the material feeding into the machine. In the construction shown the end wall 16 is provided with a centre panel 17 which is mounted for sliding vertical movement relative to the upper stationary portion 19 so that the height of the opening at the "wet" end of the hood can be adjusted to suit the machine hooded.

With particular reference to Figure 9, showing in transverse cross-section the complete enclosure and particularly the roof portion 10 which is supported directly by steel beams 11 supported from columns 13, resting on the upper frame member "C" of the machine. The columns 13 are secured to the frame members "C" at regularly spaced-apart intervals to suit the construction of the machine which is being enclosed. Suitable rafters 40, preferably of steel, are secured to the beams 11 at regularly spaced-apart relationship and the roof structure 10 is

mounted on the rafter beams 40. In the preferred construction illustrated, the roof 10 is made up of a plurality of interconnected aluminum panels which are comprised of spaced-apart sheets of aluminum having a packing 41 of insulating material, for example, Fiberglas, therebetween. These panels are mounted directly over the rafters 49 with a suitable insulation pad 42 therebetween at each joint to provide a complete insulated roof extending above the entire machine.

As indicated generally in Figure 2, suitable openings 42, 44, 46 are provided in the roof 10 and by means of air-conditioning ducts F, the moisture-laden air can be withdrawn air supplied as is well known in the art.

In the construction illustrated the longitudinal side walls 12 and 14 are made up of a plurality of segments or panels which are aligned in parallel upper and lower rows to form the enclosure walls. The lower segments or door panels 29 in the side wall 12 are mounted relative to the upper segments 22 which are fixed, so as to be capable of vertical sliding movement towards and away from the mill floor "A." The doors 20 illustrated are preferably arranged so that more than one door is raised simultaneously by single motor, as will be described later, and control means are provided whereby all the doors 20 extending along the length of the side wall 12 of the machine can be raised simultaneously. The longitudinal side wall 14 extending along the opposite side of the machine also includes upper and lower segments or door panels 24, 26 which are arranged to be slidably movable in a horizontal direction.

The end wall 16 of the hood adjacent the "wet" end of the machine is also provided with a slidably movable centre portion 17, as previously described. Access doors 32, 33 are provided in each of the end walls 16, 123 which are mounted for sliding vertical movement at one side of the centre opening of the respective end walls.

As will be appreciated, while the longitudinal side wall 12 shown consists of stationary upper doors 22 and lower vertically-slidable doors 20, and the longitudinal wall 14 includes horizontally-slidable doors 24, 26, this arrangement is illustrative only and the arrangement of the doors can be varied as desired, providing that on one side of the machine vertically slidable doors are provided giving ready access to the whole length of the machine so enclosed.

Vertically-slidable doors

The vertically-slidable doors 20 which form the lower portion of the longitudinal side wall 12 are each mounted between guide channels 70 positioned in spaced-apart relationship on the upper half of the side wall. The guiding members 70 each constitutes a channel having outstanding flanges 72 wherein guiding rollers 76 mounted at each side of the door panels 20 are maintained in alignment during the travel of the doors. The rollers 76 are positioned adjacent the top portion of the doors only as is shown in detail in Figures 12 and 14, the lower portion of the door being guided through the contact of bordering channels 81 which overlap the guiding channels 70 as shown in Figure 15.

The sliding doors or panels 20 are each made up of juxtaposed sheets of corrugated aluminum which are joined centrally and connected at each side to the channel members 81. A typical cross-section of these doors is shown in Figure 16.

In order that an adequate support be provided for the guiding and lifting means utilized in the operation of the vertically sliding doors a supplementary framework 50 is provided on the side of the enclosure having the longitudinal side wall 12. The framework 50 extends outwardly from the roof portion 10 to beyond the eaves portions 9 and then downwardly to a position approximately halfway to the mill floor "A." This frame is cross-braced at the lower end by spaced-apart longitudinal braces 52 which extend from the machine frame members

"C." The bracing members 52 extend diagonally from the frame "C" to a connection with the frame members 54 which extend downwardly from the eaves portions 9 of the roof. The frame members 50, 54 and the diagonal braces 52 are disposed in spaced-apart relationship along the length of the hood enclosure as will be described in more detail later.

The doors 20 are raised or lowered relative to the mill floor "A" through the medium of a plurality of spaced-apart winding drums 80. The drums 80 are mounted in opposed pairs on shafts 84 each of which are journaled in suitable bearings 51 supported by the frame members 50. Driving gears 82 are also connected to certain of the shafts 84 so that driving motors 86 may, through a transmission 88, and a chain drive 90, provide the necessary rotative movement to the shafts 84. The shafts 84 are disposed in axial alignment and in interconnected groups so that through the action of a single motor more than one pair of winding drums 80, and, consequently, more than one door panel 20 is raised; for example, as illustrated, three panels are so connected in the present construction.

In the case where more than one shaft 84 is to be driven by the same motor, for example three adjacent shafts as shown, the adjacent shaft ends 83 are coupled by a flexible coupling 85 as shown in Figure 17. In between each connected group of shafts, as is shown in Figure 18, there is no coupling between the adjacent shaft ends. It should also be noted that the drums 80a, 80b on each shaft 84 are left and right hand with respect to each door panel 20, a connection being made from each drum to a fitting 23 provided at each side of each door 20. A flexible cable 81' extends about each respective drum surface and is connected by a suitable shackle 87 to the connecting member 23 at each side of each door 22.

In order to facilitate the lifting of the doors 20 counterweights 100 are provided which are housed in suitable channel members 102 secured to the frame members 54 adjacent each lifting section. The counter-weights 100 are connected by flexible cables 103 to extensions 106 which extend above each side of the sliding doors 22 as is shown in Figure 14.

In the preferred arrangement, each motor 86 is controlled from a master control panel indicated at "H" on Figure 1 so that each section of three doors can be lifted as required or alternatively all the doors 20 can be lifted simultaneously to provide access to the entire length of the machine.

The control panel is of the usual type having manually operated switches or buttons controlling the motors 86 and therefore is not illustrated in detail. It is also contemplated that automatic switch operating means might be employed in cooperation with the control panel "H" for example, electronic web scanning means, or web supported rolls or feelers, whereby the doors 20 would be raised automatically by the breaking of the web as it passes over the drying rollers.

On the opposite side of the enclosure, where the horizontally slidable doors 24, 26 are mounted to constitute the longitudinal side wall 14, bracing members 61 are also provided as extending from an internal catwalk "K" which extends the length of the machine. The bracing members 61 are disposed in spaced-apart relationship and serve to support the combined panels or doors 24, 26 against sideways motion. As will be appreciated, this structure is illustrative only and is peculiar to the arrangement shown. In other and similar arrangements where there might possibly be no catwalk similar bracing members would be provided from the machine frame to strengthen and support the side wall structure.

In order to maintain the maximum of sealing efficiency in the enclosure the lower edge of the doors 20 are provided with resilient sealing strips 21, see Figure 11.

The doors 24, 26 are also provided with resilient rubber or sealing strips 27a, 27b which extend between

the adjacent offset doors, as shown in Figures 7 and 8. As the lower doors 24 are offset or staggered it is possible to provide an access opening approximately half the length of the enclosure by pushing all the doors to one end or to each side if an access opening is required between the end walls. In the construction illustrated certain of the panels 26 are fixed while others are mounted for sliding horizontal movement. The doors 24 in the lower portion of the side wall 14 are all mounted for horizontal sliding movement. The slidably mounted doors 26 and 24 are provided with rollers 202 which ride in channel members 204 suspended from the supporting framework adjacent the eaves portions 9. The fixed panels 26 are secured directly to a bracket member 206 extending along the eaves portion 9. The lower portions of the doors 26, 24 are guided in channel sections 210 and 212 respectively the channel sections 212 being embedded in a concrete curb "M" extending above the mill floor "A," see Figure 13.

The construction of the doors 24, 26 is similar to that shown and described in connection with the doors 20 the main structural features being their strength and lightness due to the use of the corrugated panels and also the fact that in a like manner to the doors 20, 22, the doors 24, 26 are hung from the roof structure rather than being supported by a framework arising from the mill floor.

The end walls 16 and 18 are also of similar construction with the main fixed panels being supported from the beams 40 and the individual panels joined and stiffened by channel sections secured to the adjacent marginal edges of the panels and connected as shown in Figure 23. The vertically sliding access door 33 is mounted between channel members 220, 221 as shown in Figure 27 and is provided with rollers 224 at each side to reduce friction. A suitable counterweight 222 is connected to the door 33 by means of a flexible cable 226 passing over pulley 228 so that the door can be raised manually if required. A similar arrangement is provided at the end wall 16 in connection with the door 32. Both the door 32 and the door 33 are provided with sealing strips along the lower marginal edge, see Figure 22.

The vertically adjustable panel 17 on the end wall 16 is also mounted between guiding channel members. As this panel is of greater area and is to be adjusted relative to the machine which is hooded there is provided a chain drive arrangement 230 which operates a shaft 232 mounted in suitable bearings so as to extend across the end wall 16. Sprocket gears 234 are mounted on the shaft 232 and sprocket chains 236 extend about the gears 234 to a connection with each end of the panel 17. With this arrangement, rotation of the chain drive 230 causes the gears 234 to wind up the chains 236 raising or lowering the panel 17 depending on the direction of rotation.

In the structure illustrated suitable hand rails "L" and access ladders "N" are provided for the purpose of adjustment and service. As previously recited, these are specific to the structure shown and other and similar hood structures might be constructed in accordance with the invention without these features.

I claim:

1. A hood structure for use in combination with a high speed paper drying machine, comprising a self-supporting enclosure having a roof portion of sufficient length to cover said machine and of slightly greater width to extend beyond said machine at each side, end walls disposed at each end of said roof portion each having an open central section extending across a major portion of the width of said enclosure to provide entry and exit passages for material processed on said machine, longitudinal side walls co-extensive in length with said roof portion and connecting with said end walls at each end, at least one of said side walls being made up of a plurality of juxtaposed panels disposed in two parallel rows forming upper and lower sections extending the length of said enclosure with the panels of said lower section being mounted for

vertical and sliding movement into and out of overlapping relationship with said upper panels between spaced apart guiding members mounted on said side wall upper portion and extending from adjacent the said roof portion to adjacent the juncture between said upper and lower panels, said lower panels having bordering frame members at each side extending from adjacent the lower marginal edges to beyond the upper marginal edges of said panels and being slidably engaged with said spaced apart guiding members, panel moving means mounted on said roof portion connected to each of said lower panels, and control means connected to and adapted to actuate all or part of said panel moving means.

2. A hood structure as claimed in claim 1, wherein said means for moving said panels comprises, a plurality of winding drums mounted in opposed spaced apart pairs on individual shafts, each of said shafts being mounted adjacent said roof portion for rotation above each of said vertically movable lower panels, said shafts being aligned axially along the length of said enclosure, flexible cables extending from each pair of said drums to a connection with the sides of each of said movable panels, and driving motors connected to said shafts, said driving motors being actuated through said controlling means.

3. A hood structure as claimed in claim 2, wherein said drum shafts are axially interconnected in series of three by coupling members extending from the adjacent ends of said shafts, and there is a single driving motor connected to each coupled unit.

4. A hood structure as claimed in claim 1, wherein one of said end walls includes a panel mounted for sliding movement relative to said central opening whereby the area of said opening may be adjusted relative to the height of said opening.

5. A hood structure adapted for use in combination with a high speed paper drying machine, comprising a self-supporting enclosure having a roof portion of sufficient length to cover said machine and of slightly greater width to extend beyond said machine at each side, end walls disposed at each end of said roof portion, each of said end walls having an open central section adapted to provide entry and exit passages for material processed on said machine, longitudinal side walls co-extensive in length with said roof portion and connecting said end walls at each end, each of said side walls being made up of a plurality of juxtaposed panels disposed in two parallel rows forming upper and lower sections extending the length of said enclosure with the panels on the upper and lower sections of one side wall being mounted for horizontal sliding movement relative to each other, and the panels of the lower section of the other side wall being mounted for vertical sliding movement relative to the upper section by guiding members mounted in spaced apart relationship between the upper panels of said second side wall and terminating adjacent the juncture of said upper and lower panels, guiding channels on each side of each of said lower panels slidably engaged with said guiding members, panel moving means mounted on said roof portion connected to and adapted to move said second side wall lower section panels into and out of overlapping relationship with the upper portions of said side wall, and control means adapted to actuate all or part of said panel moving means.

6. A hood structure for use in combination with a high speed drying machine having a supporting frame extending upwardly from a mill floor, comprising a roof portion coextensive in length with said machine and being supported from the upper portion of said machine frame, longitudinal side walls co-extensive in length with said roof portion extending from said roof portion to said mill floor, one of said side walls having an upper portion and a lower portion with said lower portion made up of a plurality of juxtaposed vertically slidably movable panels guided and supported solely from the upper portion of said wall by spaced apart panel guiding members

mounted on said wall upper portion and extending from adjacent the top of said wall upper portion to terminate adjacent the lower marginal edge of said wall upper portion, whereby said lower wall panels are adapted when raised to provide a clear, unobstructed passage from said mill floor to said side wall upper portion along the entire length of said machine, panel moving means mounted on said roof portion connected to each of said slidably movable panels and control means connected to said panel moving means.

7. A hood structure as claimed in claim 6, wherein said means for moving said vertically movable panels comprises a plurality of winding drums mounted in opposed spaced apart pairs on individual shafts, each of said shafts being mounted for rotation above each of said movable panels adjacent said roof portion, said shafts being aligned axially along the length of said enclosure, flexible cables extending from each pair of said drums to a connection with the sides of each of said movable panels, and driving motors connected to said shafts, said driving motors being connected to said controlling means.

8. A hood structure as claimed in claim 6 including end walls each having a central open portion extending across a major portion of the width of said enclosure, one of said end walls having a panel mounted for vertical and sliding movement relative to said central opening whereby the area of said opening may be adjusted relative to the height of said opening.

9. A hood structure for use in enclosing a high speed paper machine of the type having at least a portion extending upward from the mill floor, said hood structure comprising a self-supporting structure mounted directly on the frame of said machine and including a roof portion of a length substantially equal to the machine to be enclosed and a width slightly greater than said machine so as to extend beyond said machine at each side, said enclosure including side walls co-extensive in length with said roof portion and extending from said mill floor to said roof portion, and end walls connecting said roof and side walls at each end and having side portions extending from said mill floor to said roof and a central portion extending across a major portion of the width of said enclosure from said roof and terminating short of said mill floor to provide entry and exit passages for the feeding of material through said machine, one of said enclosure side walls being made up of a plurality of juxtaposed upper and lower panels extending the length of said side wall, a plurality of guiding members fixedly

mounted in spaced relationship along the length of said upper panels, said guiding members extending from adjacent the roof of said enclosure to terminate at the lower margin of said upper panels, said lower panels each being 5 provided with bordering guiding channels at each side slidably engaged with said spaced guiding members whereby they are mounted for vertical sliding movement relative to said upper panels, and means for moving said lower panels to provide unobstructed access to said machine along the length of said side wall and between said mill floor and the lower marginal edges of said panels.

10. A hood structure as claimed in claim 9 wherein the means for moving said panels comprises a plurality of winding drums mounted in opposed spaced apart pairs 15 on individual shafts, each of said shafts being mounted for rotation above each of said movable panels adjacent said roof portion, said shafts being aligned axially along the length of said enclosure, flexible cables extending from each pair of said drums to a connection with the sides 20 of each of said movable panels, driving motors connected to said shafts, and control means adapted to selectively actuate said driving motors.

11. A hood structure as claimed in claim 9, wherein the other of said side walls comprises a plurality of juxtaposed upper and lower panels extending the length of said side walls, and said upper and lower panels are mounted for horizontal sliding movement relative to each other, said panels each being arranged in staggered relationship to each adjacent panel.

12. A hood structure as claimed in claim 9, wherein one of said end walls includes a panel mounted for sliding vertical movement relative to said central opening whereby the area of said opening may be adjusted relative to the height of said opening.
